UNITED STATES PATENT OFFICE.

BYERS W. KADEL, OF BALTIMORE, MARYLAND, ASSIGNEE, BY MESNE ASSIGNMENTS,
TO THE SYMINGTON COMPANY, A CORPORATION OF MARYLAND.

DRAFT-GEAR ATTACHMENT.

Application filed January 23, 1922. Serial No. 531,237.

To all whom it may concern:

Be it known that I, BYERS W. KADEL, a citizen of the United States, residing at Baltimore, in the State of Maryland, have invented certain new and useful Improvements in Draft-Gear Attachments; and I do hereby declare the following to be a full, clear, and exact description of the invention, such as will enable others skilled in the art to which it appertains to make and use the same.

My invention relates to draft gear attachments by means of which the shocks delivered in service to draft gear mechanism are communicated to the frame of a railway car. The primary object of the invention is to afford draft gear attachments which may be readily manufactured, will efficiently meet the demands of service conditions, and which may be secured to the car framing with a comparatively slight expenditure of labor.

The principal feature of the invention, generally stated, consists in providing a member having a striking plate portion and downwardly extending spaced portions integrally united to said plate portion and adapted to be secured to the center sills or draft sills of a car, and in securing to said sills a plurality of cheek-plates whose inner faces at their forward ends overlap and contact the outer faces of said downwardly extending portions.

A further feature of the invention consists in providing a striking plate which extends between and is adapted to be secured to the center sills or draft sills of a car, and in applying to said sills a plurality of cheek-plates each having a forward face abutting the rear face of the striking plate.

Another feature of the invention involves the employment of a frame having a striking plate portion, a coupler carrier portion, and spaced side portions integrally uniting said plate and carrier portions and adapted to be secured to the center sills or draft sills of a car, combined with a plurality of cheek-plates adapted to be secured to the sills, each of said cheek-plates being formed with a key-receiving slot, and each of said side portions having rearwardly opening recesses respectively registering with the forward ends of the corresponding slots in the cheek-plates.

There are other features of the invention, residing in particular structural details and in the relations of parts, all as will hereinafter appear.

While the drawings chosen for the purpose of explaining the invention illustrate a particular form of draft gear with which attachments embodying the invention are especially well suited to be used, it is to be understood that the invention, the scope whereof is pointed out in the claims, is not limited in its application to the particular form of draft gear shown.

Figure 1 is a vertical central section of a construction embodying the invention, showing a portion of the draft gear with which the attachments are associated and a part of the car to which they are applied.

Figure 2 is a view, partly in plan and partly in horizontal section, on the line 2—2, Fig. 1.

Figure 3 is a view, partly in end elevation and partly in vertical section, on the line 3—3, Fig. 1.

Figure 4 is a view, partly in plan and partly in horizontal section, showing the relation of the draft gear and the draft gear attachments to the car.

Figure 5 is a detail sectional view on the line 5—5, Fig. 1.

In the drawings 1 indicates the spaced center sills or draft sills of a car, and 2 is the car end sill. In the construction shown in the drawings these sills are of channel form.

The draft appliances illustrated comprise a car coupler 3 connected to the forward end of a horizontal yoke 4 by a transversely extending key 5 whose outer ends project through slotted cheek-plates 6 secured to the inner sides of the center sills 1. In buffing the rear end of the yoke 4 is adapted to bear against the forward face of a backstop or abutment member 7 which is interposed between and secured to the center sills. Within the yoke are a pair of relatively movable followers 8 and 9, respectively, the former being adapted to be forced rearwardly by the coupler 3 in buffing and the latter to be drawn forwardly by the yoke when the coupler is subjected to draft. Between the followers is a suitable cushioning unit, diagrammatically

indicated by the diagonal dotted lines 10 in Fig. 4 of the drawings.

The cheek-plates 6, as is customary, constitute means for communicating to the car underframe the pulling forces to which the draft gear is subjected in service. They are rigidly riveted to the inner sides of the respective center sills 1 and at their forward ends are overlapped, as indicated 10 at 11, by the neighboring side portions 12 of a frame 13 which extends between the center sills 1 and is rigidly secured thereto as well as to the transverse end sill 2. On their outer faces the side portions 12 15 of the frame are preferably formed with recesses 14 receiving the forward ends of the cheek-plates, thus allowing the cheek-plates 6 and the frame 13 to overlap each other and at the same time to engage the 20 adjacent center sills directly.

The frame member 13 is provided with a striking plate portion 15 from which extend downwardly spaced side portions 12 designed to engage the inner faces of the 25 sills 1 and to be riveted thereto. The side portions 12 which are preferably cast integral with the striking portion 15 may themselves be integrally united at their lower ends by a coupler carrier member 30 16 on which the car coupler is slidably supported. The rear face of the striking plate 13 abuts the forward face of the end sill 2, the said striking plate being for such purpose provided with suitable bosses 17 35 surrounding the holes for receiving the rivets securing the plate to the end sill. The striking plate portion of the member 13 is preferably of channel cross section having front and rear flanges 18 and 19, 40 respectively, of unequal height, the latter being of greater height and overlapping the end sill. Extending between and integrally uniting the flanges 18 and 19 are inclined webs 20 which serve effectively to 45 transmit to the rear flange 19 the shocks incident to the impact of the coupler 3 against the forward flange 15 of the striking plate.

The forward ends of the cheek-plates 6 50 are of notched form on their upper sides to receive portions of the striking plate 13, thus providing on said cheek-plates upwardly extending portions 21 which abut the rear face of the striking plate, the latter, as clearly shown in Fig. 5, being formed 55 with raised portions or bosses 22 which contact the respective cheek-plates. Where, as shown in the drawings, the character of draft gear employed necessitates furnishing the cheek-plates with stops forming abutments for the forward follower 8, the portion 21 of the cheek-plates may be advantageously fashioned as follower stops, the said stops thus having the advantage 60 of being supported by the striking plate 65

portion 15 of the member 13. While the stops for cooperating with the follower 8 of the type of draft gear illustrated may be of any suitable form, it is preferred to construct them as shown in the drawings, 70 the lower stop portion 23 of each cheek-plate being spaced from the upper stop portion 21 a distance sufficient to permit the draft yoke 4 to operate between them.

Each of the cheek-plates 6 is fashioned 75 with a slot 24 for receiving the key which passes through the shank of the car coupler 3 and the arms of the draft yoke 4. The length of these slots is such as to permit the coupler to have the desired travel in draft and in buffering. Between the striking plate and coupler carrier the side portions 12 of the frame 13 are formed with rearwardly opening recesses 25 registering 80 with the forward ends of the slots 24 in the respective cheek-plates. Such a construction not only permits a substantial overlapping of the cheek-plates and the frame 85 13 without an undue extension of the cheek-plates, but it also serves to increase the bearing area for the key 5 at the forward ends of the cheek-plate slots.

Those familiar with this art will perceive 90 that draft gear attachments constructed in accordance with my invention greatly strengthen and stiffen the car underframe, and also considerably reduce the difficulties of effecting the alinement of rivet holes in the operation of securing attachments to car underframes.

I claim:—

1. Draft gear attachments comprising a frame having a striking plate portion, a coupler carrier portion, and spaced side portions integrally uniting said striking plate and carrier portions, and a plurality of cheek-plates adapted to be secured to the sills of a car, the said side portions of said frame being adapted to extend between and respectively to engage the inner sides of said cheek-plates at the forward ends of the latter.

2. Draft gear attachments comprising a frame having a striking plate portion, a coupler carrier portion and side portions integrally uniting said striking plate and carrier portions, and a plurality of cheek-plates adapted to be secured to the sills of a car, the said side portions of the frame being recessed on their outer faces to receive the forward ends of the respective cheek-plates.

3. Draft gear attachments comprising a member having a striking plate portion and downwardly extending spaced portions integrally united thereto and adapted to be secured to the sills of a car, and cheek-plates adapted to be secured to said car sills, said downwardly extending portions having their outer faces contacting the forward ends of the respective cheek-plates.

4. Draft gear attachments comprising a member having a striking plate portion and spaced portions integrally united to and extending downwardly from said plate portion and adapted to be secured to the sills of a car, and cheek-plates adapted to be secured to the car sills, the forward ends of said cheek-plates being in overlapped relation to the said downwardly extending portions, each of said cheek-plates being provided with a key-receiving slot, and each of said downwardly projecting portions having a rearwardly opening recess registering with the forward end of the slot in the adjacent cheek-plate. 15
5. Draft gear attachments comprising a frame having a striking plate portion, a coupler carrier portion, and spaced side portions integrally uniting said plate and carrier portions, and a plurality of cheek-plates adapted to be secured to the sills of a car, the outer faces of said side portions being recessed to receive the forward ends of said cheek-plates, each of said cheek-plates being formed with a key-receiving slot, and said side portions having rearwardly opening recesses respectively registering with the forward ends of said slots in said cheek-plates. 25
6. Draft gear attachments comprising a frame having a striking plate portion, a coupler carrier portion, and side portions integrally uniting said plate and carrier portions, and cheek-plates adapted to be secured to the sills of a car, said cheek-plates having their forward ends overlapping the outer faces of said side portions below the said striking plate portion. 30
7. Draft gear attachments comprising a frame having a striking plate portion, a coupler carrier portion, and spaced side portions integrally uniting said plate and carrier portions, and a plurality of cheek-plates adapted respectively to be secured to the sills of a car, the outer faces of said side portions being recessed to receive the respective cheek-plates, and said cheek-plates having their forward ends engaging said side portions below said striking plate portion. 45
8. Draft gear attachments comprising a frame having a striking plate portion, a coupler carrier portion, and spaced side portions integrally uniting said plate and carrier portions and adapted to be secured to the sills of a car, and cheek-plates adapted to be secured to the car sills, the forward ends of said cheek-plates being interposed between the corresponding car sill and the adjacent side portion of said frame, and each of said cheek-plates being provided with a follower stop which extends upwardly behind said striking portion of the frame in proximity to the latter. 55
9. Draft gear attachments comprising a member having a striking plate portion and spaced downwardly extending portions integrally united to said plate portion and adapted to be secured to the sills of a car, 70 and a plurality of cheek-plates adapted to be secured to said sills and having their forward ends overlapping said side portions, each of said cheek-plates being provided with an upper follower stop, and said striking plate portion being extended upwardly above said follower stops to provide means for securing it to a transverse end sill of the car. 75
10. Draft gear attachments comprising a member having a striking plate portion and side portions integrally united to and extending downwardly from said plate portion and adapted to be secured to the sills of a car, and a plurality of cheek-plates overlapping said side portions and adapted to be secured to said sills, the said striking plate portion being of channel cross section having flanges of unequal height, the said flanges being integrally united by a plurality of spaced webs, and the flange of greater height being adapted to overlap and to be secured to an end sill of the car. 80
11. Draft gear attachments comprising a frame having a striking plate portion, a coupler carrier portion, and spaced side portions integrally uniting said plate and carrier portions and adapted to be secured to the sills of a car, and cheek-plates adapted to be secured to said sills, said striking plate being of channel cross-section and comprising a pair of spaced upright flanges, the inner flange being of greater height than the outer flange to afford means for securing said frame to the end sill of the car and inclined webs integrally uniting said flanges. 95
12. Draft gear attachments comprising a striking plate extending between and adapted to be secured to the center sills or draft sills of a car, and a plurality of cheek-plates adapted to be secured to said sills, each of said cheek-plates having a portion abutting a portion of said striking plate and additional portions of said cheek-plates being adapted to overlap portions of said striking casting, and means for connecting said overlapping portions. 110
13. Draft gear attachments comprising a frame having a striking plate portion, a coupler carrier portion, and spaced side portions integrally uniting said plate and carrier portions and adapted to be secured to the sills of a car, and cheek plates adapted to be secured to said sills, said striking plate portion being of channel cross-section having an inner flange of greater height than the outer flange and having inclined webs integrally uniting said flanges, 125 130

said inner flange being extended upwardly to afford means for securing said frame to an end sill of the car.

14. Draft gear attachments comprising a striking plate extending between and adapted to be secured to the center sills or draft sills of a car, and a plurality of

cheek-plates adapted to be secured to said sills, the upper sides of said cheek-plates at their forward ends being of notched form 10 to receive portions of said striking plate.

In testimony whereof I affix my signature.

BYERS W. KADEL.
